UNITED STATES PATENT OFFICE.

JACOB C. EICHHORN, OF DETROIT, MICHIGAN, ASSIGNOR TO THE VICTOR JAR COMPANY, OF DETROIT, MICHIGAN, A CORPORATION OF MICHIGAN.

CLOSURE FOR VESSELS.

1,088,133.

Specification of Letters Patent.

Patented Feb. 24, 1914.

Application filed July 17, 1912. Serial No. 709,385.

To all whom it may concern:

Be it known that I, JACOB C. EICHHORN, a citizen of the United States of America, residing at Detroit, in the county of Wayne 5 and State of Michigan, have invented certain new and useful Improvements in Closures for Vessels, of which the following is a specification, reference being had therein to the accompanying drawings.

10 This invention relates to a jar closure and seal whereby a wide mouthed vessel may be readily sealed by means which are applied without the use of tools and which are arranged to permit the removal and replacement 15 of the receptacle closure as desired without difficulty or inconvenience to the user.

The invention consists in the matters hereinafter set forth and pointed out in the 20 claim.

In the drawings, Figure 1 is a plan view of a receptacle closure and clamping means therefor that embody features of the invention; Fig. 2 is a view of the upper portion 25 of the vessel, partially broken away and partially in section; Fig. 3 is a view in perspective, enlarged, of a clamping strip.

Referring to the drawings a receptacle 1 has a flange 2 encircling its mouth which is 30 of the full diameter of the vessel. A closure 3 of appropriate shape and design, has a rim 4 that conforms to and rests on the flange 2 over an interposed washer 5 of suitable material, when the closure is in position. The 35 rim has a hollowed or concave upper face 6. Clamping strips that consist each of a body 7 bent to conform to the peripheries of the flange 2 and rim 4 with lower inturned lugs 8 underrunning the flange 2 and upper 40 spring fingers 9 each preferably opposite a lug 8, are disposed at intervals around the mouth of the vessel. The fingers 9 of each strip are bent to conform to the curved face

6 of the rim 4 their outer ends being upturned and the space between the bend of 45 each finger and the inner face of the opposing lug being less than the distance between the marginal edges of the flange 2 and rim 4 so that when applied the fingers snap into position and compress the washer or packing 50 ring. To facilitate the removal of the strip the end portions 10 thereof extend beyond the fingers 9 and are bent outward slightly for finger pulls whereby the strips may be readily removed. As a result of this construction a closure may be readily attached to a receptacle without the use of tools and the joint at the mouth thereof be made tight, the closure being removable and replaceable at will. 60

Obviously, changes in the details of construction may be made without departing from the spirit of my invention and I do not care to limit myself to any particular form or arrangement of parts. 65

What I claim is:—

The combination with a receptacle and a closure therefor, of a comparatively flat strip adapted to engage a segmental portion of said receptacle and extending longitudinally 70 of the meeting edges of said closure and said receptacle, spaced apart lugs and fingers carried by the marginal edges of said strip and adapted to frictionally and detachably engage said receptacle and the closure thereof, 75 said strip having the ends thereof bent in a plane directed from the periphery of said receptacle whereby the ends of said strip can be gripped and said strip removed.

In testimony whereof I affix my signature 80 in presence of two witnesses.

JACOB C. EICHHORN.
